INCUBATOR

Albert Henry Brain, Great Barr, West Bromwich,
and Frederick George Timmins, West Brom-
wich, England, assignors to Charles Hearson &
Company, Limited, London, England, a com-
pany of Great Britain

Application August 28, 1933, Serial No. 687,148
In Great Britain April 14, 1932

10 Claims. (Cl. 119—37)

This invention relates to improvements in incubators and has for its object to provide a generally improved construction in which the air within the incubator will be efficiently mixed and substantially uniformly distributed throughout the body of eggs being incubated and/or hatched.

Referring to the drawings:—

Figure 1 is an end elevational view, partly in section, of one form of incubator constructed in accordance with this invention.

Figure 2 is a longitudinal elevational view, partly in section taken on lines 2—2 of Figure 1.

Figure 3 is an enlarged detail of part of the structure shown in Fig. 2.

Figure 4 is a perspective view of a detail.

Figure 5 is a substantially longitudinal sectional view of a modified construction.

Figure 6 is a circuit diagram of the heaters and thermostats.

In the construction illustrated in Figures 1 to 4 of the accompanying drawings the incubator comprises a casing or container 6 divided into an incubating compartment 7 and a hatching compartment 8 by means of a transverse partition 9 extending entirely across the section of the casing so as to separate entirely the two compartments.

In the incubating compartment the trays for the eggs being incubated are mounted for periodic tilting movement, and all these trays, such as are shown at 10, are mounted in a common framework so that by moving this frame all the trays mounted therein can be tilted in unison.

The frame is constructed from angle section metal and comprises an outer skeleton box-like frame 11 with stiffening members 12 of strip metal across the back and with transverse guides 13 of angle section for the trays to be inserted in the frame.

The frame is mounted for limited rotation about a horizontally disposed shaft 14 and is supported on the shaft by means of ball bearings located in each of two bearing plates 15 secured to the frame 11 by means of diagonals 16 of strip metal.

The various members of the frame may be secured together by rivets or by spot welding, and the diagonals 16 may be secured to the frame 11 and to any of the transverse guides 13 across which the diagonals pass.

The shaft 14 is adapted for continuous rotation within the casing, and in order to ensure mixing and circulation of the air within the casing, mixing members are mounted on the shaft, one on either side of the frame 11. A further mixing member is mounted on the end of the shaft projecting through the transverse partition 9, this last mentioned mixing member being

adapted for rotation in the hatching compartment 8.

Each mixing member comprises a central boss 17 keyed or otherwise secured to the shaft and four blades 18 secured to the boss project substantially radially therefrom. The blades are secured to projecting ribs 19 on the boss, these ribs being formed integral with the boss or secured thereto, and rivets or screws may be used for connecting the blades to the projections.

Each blade is twisted or bent out of the common plane through the centre lines of the blades, as shown clearly in Figure 3, so that the air is in part directed parallel to the axis of rotation and through the trays supported within the compartment. The mixing members in each compartment are constructed as described above, but the inclination or twisting of the blades is opposed in the mixers in the incubating compartment as is shown in Figure 2, so that the air currents set up by these members oppose one another to produce an efficient churning and mixing of the air and to minimize any defined currents in a single direction.

A stationary supporting frame is provided for the trays in the hatching compartment, this frame 20 being constructed in a similar manner to the frame 11 from angle section metal and with transverse horizontally disposed guides 21 also of angle section, the trays 22 being slidden into these guides from the front of the machine.

In order to prevent the trays in the hatching compartment being pushed beyond the extremities of the guides, the ends of one of the arms of the angles 21 are bent over as at 23 to project across the end of the channel, each end 23 forming a limiting stop against which the rear end of a tray engages when the latter is fully inserted in the guides. If desired, however, a strip of metal may be secured between each pair of guides across the end to function in a similar manner as a limiting stop.

In the case of the guides for the frame 11 both ends of one arm of each channel are bent across to form stops as shown at 24 in Figure 3 so as to limit the movement of the trays in both directions, and in this case when the frame is in the position with the guides 13 substantially horizontal the trays are inserted in a slightly downwardly inclined direction, namely over the stops at the forward end of the guides. When the trays are fully inserted in the frame the front edge of the tray is allowed to fall behind the stops at the front ends of the guides, and when it is desired to remove a tray the front end must be first lifted over the front stops. By this means when the frame 11 is tilted in either direction around the shaft 14 the trays are prevented from leaving the guides since the weight of the trays and the eggs retains each tray upon the guides.

13, and the stops 24 prevent these trays sliding out of the guides in either direction.

In the case of the trays 22 in which are positioned the eggs in the hatching stages or final 5 stages of incubation it is unnecessary to tilt these eggs, and the supporting frame can therefore be secured to the floor of the casing, and it is only necessary to provide stops at the rear ends of the guides.

10 In order to retain the frame 11 in an adjusted position and to control the movement from the exterior of the incubator, an arm 25 is connected to two opposite corners of the frame by means of bolts 26. This arm extends diagonally 15 across the end of the frame so that the bolts 26 are outside the extremities of the path of movement of the blades 18 as will be appreciated from the section shown in Figure 1, and at its centre part the arm is provided with a boss 27 secured 20 to one end of an annular sleeve 28 which is disposed within a sleeve 29 on a bearing plate 30 secured to the end wall of the casing.

The sleeve 28 projects through the plate 30, and a handle 31 is secured to the sleeve by means 25 of a metal strap 32 so that the frame 11 can be moved around the shaft 14 from the exterior of the incubator by operating the handle 31.

In order to limit the movements of the frame and to retain it in an adjusted position a rack 30 33 is secured to the end wall of the incubator, this rack having slots or recesses 34 at the ends and at an intermediate central point for co-operation with a spring pressed pawl moved by means of a trigger 35 provided on the handle.

35 The shaft 14 is supported in a ball race 36 mounted within the sleeve 28, a pulley 37 being secured to the end of the shaft so that this shaft and the mixing member secured thereto can be rotated continuously through a belt drive 38 from 40 a pulley shown in dotted lines at 39, this pulley being driven by a suitable electric or other motor.

The mixing members can be rotated on the shaft 14 mounted within the ball race 36 and a further race 40 mounted in a bearing plate 41 45 secured to the transverse partition 9, whilst the frame 11 can be given any desired periodic tilting movement, to alter the inclination of the eggs in the trays mounted therein, by operating the handle 31 and rotating the sleeve 28 around the ball race 36 and within the sleeve 29 of the bearing plate 30.

Ventilators of the hit-and-miss type are provided near the upper and lower horizontal edges of the ends of the casing 6 as at 42 and 43, forming 55 the outlet and inlet ventilators respectively, and each ventilator is individually controllable so that the air admitted or exhausted at any point across the section of the incubator can be controlled as desired.

60 By this means the carbonic acid content of either compartment can be adapted to the conditions required for incubating and hatching respectively. Since it is desirable to retain most of the carbonic acid in the incubator during the first stages of incubation both sets of ventilators in the incubating compartment may be retained closed for the first ten days, since the carbonic acid given off by the eggs in this period is relatively small.

70 The proportion of carbonic acid desirable for satisfactory incubation is about fifty parts in ten thousand parts of air, and such a proportion in the incubating compartment will be found satisfactory.

75 In the case of the eggs in the final stages of

incubation, namely from the eighteenth to the twenty-first day, the quantity of carbonic acid evolved is higher, and the carbonic acid content of the air in the compartment 8 may be allowed to rise to one hundred or one hundred and fifty parts in ten thousand parts of air, the ventilators being adjusted to allow these conditions.

The carbonic acid content in either compartment can be estimated by means of devices or apparatus well known for this purpose.

Electric heaters are provided at 44 and 45 in the compartment 7 and at 46 in the compartment 8, the supply to each heater being controlled by means of a thermostat illustrated diagrammatically at 47, so that when the temperature within either compartment exceeds that desirable, the supply to the heaters is cut off until the radiation from the exterior surface of the casing and the conduction through the walls reduces the temperature within the incubator, 20 when the heaters are again connected in circuit.

A water tray 48 is provided in the compartment 7, and in order to control the amount of moisture in the air in this compartment a cover 49 is provided fitting closely over the tray, this cover having a number of slots 50 extending radially from a central point, the area of slots exposed being controlled by means of a slide 51 having correspondingly formed slots and being pivoted at 52 to the cover 49. This slide is controlled through a wire or other suitable cable 53, a spring 54 being provided to move the slide into the position in which the slots are closed, and the slide being moved against the action of this spring by means of a suitable handle or control 30 knob 69 secured to the wall of the incubator.

By this means the moisture content of the air in the incubating compartment can be adjusted, and it has been found that a moisture content of about fifty per cent saturation is satisfactory 40 in the case of the incubating compartment, this being determined by means of a hygroscope or humidity indicating device of any well-known form.

A moisture tray 55 is provided in the compartment 8 without any control of the exposed area since the moisture required in this compartment is considerably higher than that required in the compartment 7, but if desired a control device as illustrated in Figure 4 may be applied to this tray as well as to the tray 48.

A door is provided for each compartment to allow access to the interior of the casing, each door being of convenient size to allow trays to be inserted into the frames 11 and 20. Glass 55 panels may be provided in each door so that the interior of the incubator can be inspected, the thermometers showing the temperature of the air within the incubator being preferably disposed on the inside of each door for inspection through the glass panel, and a suitable light may be provided in each compartment to facilitate such inspection.

In the alternative construction illustrated in Figure 5 the incubating compartment 56 and the hatching compartment 57 are disposed one above the other, being separated by a horizontal partition 58 and a vertical partition 59, the arrangement and disposition of the framework for the trays, the tilting mechanism for this framework and the mixing members being substantially 65 identical with that described with reference to the construction illustrated in Figures 1 and 2.

The mixing member for the hatching compartment comprises four flat blades 60 secured to the boss on the end of the shaft 14, since it is not 70

desired to direct part of the air longitudinally of the shaft, and this mixer is disposed within a narrow compartment 61 at the side of the compartment 56. The air moved by this mixer 60 is directed downwardly into the compartment 57, and an inlet ventilator is provided at 62 with an outlet ventilator at 63 for the compartment 57.

In order to obtain access to the mixing member 60 or to the bearing in the partition 59, part of the end wall, as at 64, is made removable, being secured in a readily detachable manner by means of latches or other suitable fasteners.

Heaters, water trays and thermostats are provided for the two compartments as described with reference to the previous construction, but in modified positions determined by the modifications in the construction.

The inlet ventilators for the compartment 56 are disposed at the lower horizontal edge of this compartment in the end wall as at 65, but the outlet ventilators are provided in the roof as shown at 66.

This modified construction is particularly suitable for small machines since the length is considerably reduced, and it is unnecessary to have a hatching compartment equal in area in vertical section to that of the incubating compartment, which only accommodates a single column of trays. In the case of small machines it is an advantage to reduce the effective length of the machine.

The incubator illustrated in Figure 5 functions exactly as described with reference to that illustrated in Figures 1 to 4, the modifications being structural rather than functional, and residing in the re-arrangement of the parts.

With the incubator illustrated and described the hatching compartment is entirely separated from the incubating compartment, this being desirable in that communication of disease or other infection is minimized.

When the eggs are in course of hatching, particles of fluff and other materials are deposited and these form particularly undesirable carriers of bacterial infection if any of the hatching eggs are so infected. If these particles are circulated through the entire incubator the eggs in the remaining stages may become infected. In addition, cleaning of the incubator after a cycle of operations is greatly facilitated, since the major portion of the deposit is confined to the hatching compartment.

In order to facilitate still further the cleaning operations, the supporting frame for the trays in the hatching compartment may be removable, and both compartments may have an inner metal lining, the main casing comprising one or more layers of wood with or without intermediate packing of heating insulating material.

What we claim then is:—

1. An incubator comprising an interiorly heated casing, a group of egg trays in said casing, a supporting frame for said trays, a shaft mounted horizontally in said casing, bearings for supporting the said frame on the said shaft, said supporting frame being mounted for oscillatory movement around said shaft to tilt eggs in said trays, means for restraining said frame in certain definite positions, a mixing member on said shaft at each side of said frame, means for rotating said shaft and the mixing members therewith, each mixing member having a number of blades shaped to direct air in part laterally of the mixing member and between the egg trays, and the shaping of the blades of the two mixing

members being opposed so that air currents are set up in opposite directions to mix and churn the air in the casing.

2. An incubator comprising an interiorly heated casing, a group of egg trays in said casing, a supporting frame for said trays, a shaft mounted horizontally in said casing, bearings for supporting the said frame on the said shaft, said supporting frame being mounted for oscillatory movement around said shaft to tilt eggs in said trays, means for restraining said frame in certain definite positions, a mixing member on said shaft at each side of said frame, each mixing member having a number of blades extending radially from a central boss, the leading face of each blade being inclined to the common plane through the centre lines of the blades to direct air in part laterally of the mixing member, and means for rotating said shaft and the mixing members therewith.

3. An incubator comprising an interiorly heated casing, a group of egg trays in said casing, a supporting frame for said trays, a shaft mounted horizontally in said casing, bearings for supporting the said frame on the said shaft, said supporting frame being mounted for oscillatory movement around said shaft to tilt eggs in said trays, means for restraining said frame in certain definite positions, a mixing member on said shaft at each side of said frame, means for rotating said shaft and the mixing members therewith, each mixing member having a number of blades extending radially from a central boss, the leading face of each blade being inclined to the common plane through the centre lines of the blades to direct air in part laterally of the mixing member, and the inclination of the blades of the two mixing members being opposed, so that air currents are set up in opposite directions to mix and churn the air in the casing.

4. An incubator comprising an interiorly heated casing, a transverse partition dividing said casing into separated incubating and hatching compartments, a group of egg trays in said incubating compartment, a supporting frame for said trays, a shaft mounted horizontally in said casing, a bearing in said transverse partition, a further bearing in the casing wall parallel to said partition, said shaft being supported in said bearings for rotary movement, said supporting frame being mounted for oscillatory movement around said shaft to tilt eggs in said trays, means for restraining said frame in certain definite positions, a mixing member on said shaft at each side of said frame, a further stationary egg tray framework in said hatching compartment, a mixing member secured to said shaft and located in said hatching compartment, and means for rotating said shaft and the mixing members therewith.

5. An incubator comprising an interiorly heated casing, a transverse partition dividing said casing into separated incubating and hatching compartments, a group of egg trays in said incubating compartment, a supporting frame for said trays, a shaft extending horizontally through said incubating compartment and projecting into said hatching compartment, a bearing in said transverse partition, a further bearing in the casing wall parallel to said partition, said shaft being supported in said bearings for rotary movement, said supporting frame being mounted for oscillatory movement around said shaft to tilt eggs in said trays, means for restraining said frame in certain definite positions, a mixing member on said shaft at each side of said frame, a further

stationary egg tray framework in said hatching compartment, a mixing member secured to the end of said shaft in said hatching compartment, each mixing member having a number of blades 5 extending radially from a central boss, the leading face of each blade being inclined to the common plane through the centre lines of the blades to direct air in part laterally of the mixing member, and means for rotating said shaft and the 10 mixing members therewith.

6. An incubator comprising an interiorly heated casing, a vertical transverse partition dividing said casing into side by side incubating and hatching compartments, a shaft extending horizontally 15 through said incubating compartment and projecting into said hatching compartment, bearings in the vertical end wall of the incubating compartment and in said transverse partition, said shaft being supported in said bearings for rotary 20 movement, means for rotating said shaft in said bearings, a group of egg trays in said incubating compartment, a supporting frame for said trays, said supporting frame being mounted for oscillatory movement around said shaft to tilt eggs in 25 said trays, means for restraining said frame in certain definite positions, a mixing member on said shaft at each side of said frame, a further stationary egg tray framework in said hatching compartment, a mixing member secured to the 30 end of said shaft in said hatching compartment, each mixing member having a number of blades extending radially from a central boss, the leading face of each blade being inclined to the common plane through the centre lines of the blades 35 to direct air in part laterally of the mixing member, and the inclination of the blades of the first two mixing members being opposed so that opposed air currents are set up to churn and mix the air in the incubating compartment, and 40 means for rotating said shaft and the mixing members therewith.

7. An incubator comprising an interiorly heated casing, a transverse partition dividing said casing into separated incubating and hatching compartments, a shaft extending horizontally through said incubating compartment and projecting into said hatching compartment, bearings in the vertical end wall of the incubating compartment and in said transverse partition for 45 supporting said shaft in said casing, means for rotating said shaft in said bearings, a group of egg trays in said incubating compartment, a supporting frame for said trays, bearings on said frame to support said frame on said shaft, said supporting frame being oscillatory on said shaft to tilt eggs in said trays, means for restraining said frame in certain definite positions, a mixing member on said shaft at each side of said frame, a further stationary egg tray framework in said 50 hatching compartment, a mixing member secured to the end of said shaft in said hatching compartment, each mixing member having a number of blades extending radially from a central boss, the leading face of each blade being inclined to the common plane through the centre lines of the blades to direct air in part laterally of the mixing member and the inclination of the blades of the first two mixing members being opposed, so that 55 air currents are set up in opposite directions to mix and churn the air in the incubating compartment.

8. An incubator comprising an interiorly heated casing, a group of egg trays in said casing, a 60 supporting frame for said trays, a shaft mounted

horizontally in said casing, said supporting frame being mounted for oscillatory movement around said shaft to tilt eggs in said trays, bearings in spaced vertical walls of said casing for supporting said shaft, the bearing in the end vertical wall of the casing having a rotatable sleeve, an arm secured to said sleeve on the interior of said casing, connections from said arm to said supporting frame, said sleeve being movable around said bearing to oscillate said frame, means for restraining said frame in certain definite positions, a mixing member on said shaft at each side of said frame, and means for rotating said shaft and the mixing members therewith. 10

9. An incubator comprising an interiorly heated casing, a group of egg trays in said casing, a supporting frame for said trays, a shaft mounted horizontally in said casing, bearings in said supporting frame for engaging said shaft, further bearings in said casing for supporting said shaft, means for rotating said shaft in said bearings, said supporting frame being oscillatory on said shaft to tilt eggs in said trays, an arm on the interior of said casing and associated with one of said bearings, connections from said arm to said supporting frame, said arm being movable with said bearing to oscillate said frame, means for restraining said frame in certain definite positions, a mixing member on said shaft at each side of said frame, each mixing member having a number of blades extending radially from a central boss, the leading face of each blade being inclined to the common plane through the centre lines of the blades to direct air in part laterally of the mixing member, and the inclination of the blades of the two mixing members being opposed, so that air currents are set up in opposite directions to mix and churn the air in the incubating compartment. 25

10. An incubator comprising an interiorly heated casing, a transverse partition dividing said casing into separated incubating and hatching compartments, a shaft extending horizontally through said incubating compartment and projecting into said hatching compartment, a group of egg trays in said incubating compartment, a supporting frame for said trays, bearings in the vertical end wall of the incubating compartment and in said transverse partition, bearings in said supporting frame for engaging said shaft, means for rotating said shaft in said bearings, said supporting frame being oscillatory on said shaft to tilt eggs in said trays, an arm on the interior of said casing and associated with one of said bearings, connections from said arm to said supporting frame, said arm being movable with said bearing to oscillate said frame, means for restraining said frame in certain definite positions, a mixing member on said shaft at each side of said frame, a further stationary egg tray framework in said hatching compartment, a mixing member secured to the end of said shaft in said hatching compartment, each mixing member having a number of blades extending radially from a central boss, the leading face of each blade being inclined to the common plane through the centre lines of the blades to direct air in part laterally of the mixing member, and the inclination of the blades of the first two mixing members being opposed, so that air currents are set up in opposite directions to mix and churn the air in the incubating compartment. 40
